UNITED STATES PATENT OFFICE.

CHARLES LARRICK, OF LOS ANGELES, CALIFORNIA.

SOUND-AMPLIFIER FOR EAR-PHONES.

1,260,689.

Specification of Letters Patent. Patented Mar. 26, 1918.

Application filed August 13, 1917. Serial No. 185,925.

To all whom it may concern:

Be it known that I, CHARLES LARRICK, a citizen of the United States, residing at Los Angeles, in the county of Los Angeles and 5 State of California, have invented new and useful Improvements in Sound-Amplifiers for Ear-Phones, of which the following is a specification.

My object is to provide a device to be applied to the transmitter of an electric ear trumpet or ear phone which will magnify the sound delivered to the ear by the receiver.

Figure 1 is an elevation of an electric ear 15 trumpet or ear phone equipped with a sound amplifier in accordance with the principles of my invention.

Fig. 2 is an enlarged front elevation of the sound amplifier with the phone transmitter removed.

Fig. 3 is a central sectional detail on the line 3—3 of Fig. 2.

Fig. 4 is an enlarged fragmentary sectional detail on the line 4—4 of Fig. 2.

25 The ear phone or electric ear trumpet consists of the battery 1, the transmitter 2, the wires 3, the rheostat 4 and the receiver 5. As shown, the transmitter 2 is circular in front and rear elevation and straight or flat 30 in side elevation or edge view, and usually a man inserts the battery 1 into the pencil pocket of his vest with the face 6 of the transmitter in front. The face 6 is a disk having a small perforated area at its center 35 for admitting the sound waves to the microphone of the transmitter. All of this is usual in "Globe ear phones" and the like.

40 My sound amplifier 7 consists of the sound collector 8, the sound concentrator 9, and the attaching frame 10.

The sound collector 8 is pressed from sheet metal and is hemispherical and hollow. Notches 11 are cut in one edge to receive the posts 12 extending from the battery 1 to the 45 transmitter 2.

The sound concentrator 9 is pressed from similar sheet metal and is hemispherical and hollow and is considerably smaller than the collector 8, and has a central concentrator 50 opening 12' and spacing legs 13 stamped from the opening. The concentrator 9 is placed in the collector 8 with the legs 13 in contact with its inner face, thereby forming the collecting chamber 14.

55 The attaching frame 10 includes a cylindrical casing 15 formed integral with the

concentrator 9, and extending to a plane substantially flush with the edge of the collector 8, thus forming an enlarged annular mouth 16 leading to the chamber 14. An annular 60 flange 17 is inserted at the bottom of the casing 15, and an annular soft rubber packing ring 18 forms a lining for the casing 15 and flange 17. Bolts 19 are inserted through the collector 8 and through web 20 extending from the 65 concentrator 9 and through web 20 extending from the flange 17.

The transmitter 2 is pressed tightly into the cushioned chamber 21 within the casing 15 against the cushioned flange 17. The 70 clamping frame, or door, 22 is connected to the edge of the casing 15 by a hinge 23. The soft rubber lining 24 is pasted to the inner face of the clamp 22 to engage the back of the transmitter 2. A hasp 25, connected to the opposite side of the clamp 22 from the hinge 23 by a hinge 26, engages the catch 27 extending outwardly from the casing 15, thereby clamping the amplifier firmly to the transmitter 2 with the face of the 75 transmitter backwardly; so that sound will enter the mouth 16, pass through the collecting chamber 14, through the central concentrator opening 12', and through the concentrating and magnifying chamber 28, then 80 through the perforated transmitter face 6 to the microphone.

The ear phone equipped with my sound amplifier, as shown and described, if used in a vest pocket will be turned with the back 90 side of the transmitter in front so as to present the mouth 16 forwardly. The forward edge of the collector 8 surrounds a considerable area and collects the sound waves of this area and transmits them through the 95 chamber 14, through the opening 12' to the chamber 28, and through the small perforated area 30 of the face 6.

In actual practice, I am hard of hearing and the "Globe ear phone" alone is only a 100 slight help to me, but since I made and applied my amplifier I can hear as readily as an average person.

Various changes may be made in the layout and details of construction, and the amplifier may be made to fit different types of transmitters without departing from the spirit of my invention as set up in the following claims.

I claim:

1. A sound amplifier, comprising a hollow hemispherical shell, a second hollow hemi-

110

spherical shell fixed within the first shell, there being an annular mouth between the edges of the shells and a central opening through the second shell, and a frame rigid 5 within the second shell and adapted to receive a transmitter with its face toward the second shell.

2. A sound amplifier comprising a hollow hemispherical sound collector having post notches in its edge, a hollow hemispherical sound concentrator mounted within the sound collector and having a central opening, spacing legs around the opening and forming a collecting chamber between the 10 concentrator and collector, a cylindrical casing extending from the rim of the sound concentrator to a plane substantially flush with the edge of the collector, an annular flange inserted inside of and at the bottom 15 of the casing, a web extending from the annular flange inside of the concentrator, a soft rubber packing ring forming a lining for the casing and the flange, and bolts inserted through the collector and through the concentrator and through the web.

3. A sound amplifier comprising a hollow

hemispherical sound collector having post notches in its edge, a hollow hemispherical sound concentrator mounted within the sound collector and having a central opening, spacing legs around the opening and forming a collecting chamber between the concentrator and collector, a cylindrical casing extending from the rim of the sound concentrator to a plane substantially flush 35 with the edge of the collector, an annular flange inserted inside of and at the bottom of the casing, a web extending from the annular flange inside of the concentrator, a soft rubber packing ring forming a lining 40 for the casing and the flange, bolts inserted through the collector and through the concentrator and through the web, a telephone transmitter fitting tightly within the packing ring with the battery posts in the 45 notches, and a clamping frame hinged to the casing and adapted to hold the transmitter in place.

In testimony whereof I have signed my name to this specification.

CHAS. LARRICK.
